TOBACCO CONTAINER

Samuel C. Baughn, East St. Louis, Ill., assignor
of one-half to John F. Wessel, East St. Louis,
Ill.

Application March 2, 1936, Serial No. 66,771

2 Claims. (Cl. 206—38)

The device forming the subject matter of this application is a combined container for matches, cigarette paper, and tobacco. The word "tobacco" is to be construed to mean loose leaf or cut plug, cigars, cigarettes or anything else that is smoked, either as an article ready for smoking as manufactured, or after some operation by a smoker, such as making a cigarette or filling a pipe.

10 The container comprises a body and a hinged lid. One object of the invention is to provide novel means for mounting the lid hingedly on the body and to provide a novel spring means for opening the lid, when the lid is released from the body. Another object of the invention is to improve the construction of the cigarette paper holder and its mounting. A further object of the invention is to improve the match holder and its mounting. Yet another object of the invention is 20 so to construct the device that when the cigarette paper holder is opened, whilst the device is held in the human hand, the hand will tend to keep the match holder closed, rather than to permit an opening of the match holder.

25 It is within the province of the disclosure to improve generally and to enhance the utility of devices of that type to which the invention appertains.

With the above and other objects in view, 30 which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawing: 40 Fig. 1 is a perspective view showing a device constructed in accordance with the invention, the cigarette paper holder being opened;

Fig. 2 is a vertical longitudinal section;

45 Fig. 3 is a vertical longitudinal section at right angles to Fig. 2;

Figs. 4, 5, and 6 are transverse sections, taken respectively on the lines 4—4, 5—5, and 6—6 of Fig. 2.

The container forming the subject matter of 50 this application preferably is made of metal and comprises a tubular body B, which is of elongated cross section, so that it can be carried conveniently in the pocket. The body B has a flat front wall 1, a flat rear wall 2 and outwardly convexed edge 55 walls 3.

The rear wall 2 is cut away as at 4, the upper edge of the rear wall being somewhat lower than the upper edges of the walls 3 and the front wall 1. The constituent material of the rear wall 2 is not entirely removed by the cutting away 5 indicated at 4. Part of the material that is left is rolled to form a first tubular anchorage socket 5, inclined slightly toward the adjacent end of the body B, as shown in Fig. 3, and located near to one of the edge walls 3. Another part of the material that is left is rolled to form a second tubular anchorage socket 6, disposed approximately parallel to the adjacent end of the body B and located near to the other edge wall 3. A third part of the material that is left is rolled to 15 form a hinge socket 7, disposed between the anchorage sockets 5 and 6, but spaced therefrom, transversely of the body B. The front wall 1 and the edge walls 3 are provided with an out-struck bead 8, disposed parallel to the upper end of the 20 body B and forming an internal seat 9 in the body. As shown at 10, the bead 8 is continued a little way inwardly upon the rear wall 2, chiefly to reinforce the wall 2 and to give it a good appearance, as Fig. 1 will disclose. 25

A lid 11 is provided and includes a depending flange 12, which has a frictional fit about the upper end of the body B, to hold the lid releasably closed. The front part of the flange 12 is provided with a finger piece 14, to aid the operator 30 in opening the lid. The back part of the flange 12 is provided with hinge sockets 15, located on opposite sides of the hinge socket 7 of the body B. In order to accommodate the hinge pintle 18, hereinafter described, and to finish off the appearance of the body, the rear wall 2 (Fig. 1) 35 may be dented outwardly as at 16, at the ends of the sockets 15.

One end 17 of a hinge pintle 18 (Fig. 3) is engaged in one of the offsets 16 on the rear wall 2. 40 Thence, the hinge pintle 18 passes through one hinge socket 15 on the flange 12 of the lid 11, through the hinge socket 7 on the rear wall 2 of the body, through the other hinge socket 15 of the lid, through the anchorage socket 6 of the 45 body and along the other offset 16, the hinge pintle 18 being continued around the inside of the body, in the internal seat 9 formed by the bead 8. The hinge pintle 18 passes out of the seat 9 and through the anchorage socket 5 on the 50 rear wall 2 of the body. Inwardly of the socket 5, the hinge pintle 18 merges into a resilient arm 19, slanting upwardly toward the lid 11 (Fig. 3), and away from the flange 12 of the lid (Fig. 4), the arm terminating in an outwardly extended 55

and angularly disposed finger 20, bearing on the flange 12 of the lid 11, in spaced relation to the hinged mounting of the lid, the hinged mounting of the lid being indicated sufficiently for the purposes of the present discussion by the socket 7 on the wall 2 of the body B. The arm 19 and the finger 20 serve to swing the lid 11 to open position, so soon as the operator swings the lid by means of the finger piece 14 enough to release the friction grip of the flange 12 of the lid on the upper end of the body B.

The bottom 21 of the body B may be held in place in any suitable way. For instance, it may have an inverted U-shaped flange 22 in which the lower end of the body B is secured. The space between the bottom 21 and the lid 11 forms a compartment for tobacco.

The holder for the cigarette papers is in the form of a shallow box-like case 23, the side of the case which is next to the wall 2 of the body B being open. An offset rod 24 extends across the inside of the case 23 and has its ends mounted in the side flanges of the case, the function of the rod 24 being to hold the cigarette papers 25 in the case 23, when the case 23 is swung to open position as in Figs. 1 and 2.

Eyes 26 are struck from the rear wall 2 of the body B. In the eyes 26, a hinge pintle 27 is mounted. The hinge pintle 27 has offset seats 28, engaging and receiving the eyes 26, as shown in Fig. 5, the construction being such that the hinge pintle cannot slide out endwise. The ends of the hinge pintle 27 are mounted in the side flanges of the cigarette paper case 23, near to the lower end of the case. The construction is such that the case 23 is hingedly mounted, it being possible to open the case 23, away from the wall 2 of the body B, into the position of Fig. 1, or into the dotted line position of Fig. 2, to the end that the cigarette papers 25 may be removed from the case.

A means is provided for holding the case 23 normally closed against the wall 2. This means embodies a coiled spring 29, disposed about the hinge pintle 27, between the seats 28, one end 30 of the spring 29 being engaged in one of the openings in the wall 2, resulting when the corresponding one of the eyes 26 is struck out. The spring 29 has an arm 31, extended lengthwise of the case 23, and engaged through an opening in the outer wall of the case 23. An outwardly inclined lever or handle 32 is secured to the lower end wall of the case 23. By pressing on the lever or handle 32, the case 23 may be moved to the open position shown in dotted line in Fig. 2, against the action of the closing spring 29.

The numeral 33 marks a match receptacle. The bottom of the match receptacle is shown at 34 and may be connected to the receptacle by means of a U-shaped bead 35, receiving the lower end of the match receptacle 33 and secured thereto. A portion of the bottom 21 of the main receptacle B is supplied on its outer surface with a roughened area constituting a match scratcher 36. The upper end of the match receptacle 33

is reduced as shown at 37 in Fig. 2, to fit within the flange 22 of the bottom 21 of the body. By any suitable means shown at 38, the upper edge of the match receptacle 33 is hingedly connected to the lower end of the wall 1 of the body B. At 5 its upper, hinged end, the match receptacle 33 has an inwardly projecting tongue 39. A hook-shaped spring 40 is secured to the bottom 21 of the body B. When the match receptacle 33 is swung to the open position of Fig. 2 (dotted line), 10 the tongue 39 engages the spring 40 and flexes the spring outwardly, the spring, therefore, having a tendency to close the match receptacle 33 toward the solid line position of Fig. 2. When the match receptacle 33 is in the closed position 15 shown in solid line in Fig. 2, the tongue 39 bears frictionally against the shank of the spring 40, and the spring, therefore, has a tendency to hold the match receptacle 33 closed.

The general utility of the device is obvious. 20 Tobacco may be carried in the body B, cigarette papers are carried in the case 23, and matches are carried in the receptacle 33.

An important feature of the invention remains to be discussed. It is to be observed that the 25 match receptacle 33 is hinged to the body B at the opposite side of the body from the case 23. Therefore, when the device is held in the human hand, as in Fig. 1, and when the thumb of the hand is placed in engagement with the handle or 30 lever 32 on the case 23, to open the case, the natural tendency of the thumb, when pressed on the lever or handle 32, is to force the human finger 41 of Fig. 1 upwardly, thereby tending to keep the match receptacle 33 closed. 35

The device is simple in construction, but affords a means whereby a smoker can carry his tobacco, and the appurtenances which commonly are employed in connection with smoking.

Having thus described the invention, what is 40 claimed is:

1. In a device of the class described, a body, a shallow box-like cigarette paper holder having an open side disposed toward the body, means for hingedly mounting one end of the cigarette 45 paper holder on the body, spring means for closing the holder against the body, and an outwardly extended finger piece on the lower end of the holder, the finger piece constituting means for opening the holder, with respect to the body, 50 against the action of the spring means.

2. In a device of the class described, a body including a bottom, a match receptacle hinged to the lower end of the body and provided with an inwardly projecting tongue, a hook-shaped 55 spring secured to the bottom of the match receptacle and comprising a shank and a curved bill, the tongue engaging the bill of the spring, to flex the spring when the match receptacle is opened, the spring then constituting a means for moving 60 the match receptacle toward closed position, the tongue having a frictional hold on the shank of the spring, when the match receptacle is closed, to aid in holding the match receptacle closed.
